UNITED STATES PATENT OFFICE.

LOUIS V. ARONSON, OF NEWARK, NEW JERSEY.

IGNITER.

1,131,655.

Specification of Letters Patent. Patented Mar. 16, 1915.

Application filed December 2, 1913. Serial No. 804,175.

To all whom it may concern:

Be it known that I, LOUIS V. ARONSON, a citizen of the United States, residing in the city of Newark, in the county of Essex and 5 State of New Jersey, have invented certain new and useful Improvements in Igniters, of which the following is a full, clear, and exact description, such as will enable others skilled in the art to which it pertains to 10 make, construct, and use the same, reference being had to the accompanying drawings, and to numerals of reference marked thereon, forming a part of this specification.

My invention relates to improvements in 15 igniters, in which the absorbent material, such as cotton for instance, saturated with benzine, gasoline or the like, is used, and has for its object, the production of a practical, new and efficient device which is extremely 20 durable and is not so liable to become inoperative when used continuously, and to this end, it consists in the detailed construction and arrangements of the parts, all as hereinafter more particularly described and 25 pointed out in the claims.

In describing my invention, reference is had to the accompanying drawings forming a part of this specification, in which like numerals indicate corresponding parts in 30 all of the views.

Figures 1 and 2 represent side elevations of two forms of my improved device, the lids being removed therefrom. Fig. 3 represents a plan view of the device illustrated 35 in Fig. 1. Fig. 4 represents a vertical section thereof. Fig. 5 represents a sectional view taken on line $\alpha-\alpha$ of Fig. 1. Fig. 6 represents a plan view of the steel striker supporting bracket and spring removed 40 from the lid of the device illustrated in Fig. 4; and Fig. 7 represents an enlarged view, partly in section, of the steel striker element illustrated in Fig. 2, and the manner in which it is secured to the case.

45 In the drawings, 1 represents an outer shell of any desired form, preferably made from a single piece of suitable material, such as brass or the like, provided with a closed bottom 2 and open top. Fitted into 50 the open top of said shell is a similar-shaped inner shell 3 of smaller dimension, also provided with an open bottom and a closed top 4, which may be secured thereto in any desired manner, preferably by frictional engagement, one with the other. These two 55 shells 1 and 3 are secured together in such

a manner as to provide a shoulder 5 to receive the open end of the cover or lid 6. The lid 6 consists of a shell of the same general outline and dimensions as the outer 60 shell 1, so that when the same is secured to the shell 1, a receptacle of neat appearance and one having unbroken surfaces is produced. 7 represents a flat spring, one end of which is provided with a reduced portion or prong 8, designed to enter an aperture formed in a U-shaped bracket 9, which carries a steel striker 10 secured thereto in any convenient manner, said spring 7 being forced into the cover or lid 6 and having 70 frictional engagement therewith, as illustrated in Fig. 4 of the drawings, thereby positioning the bracket 9, with the striker projecting beyond the open end of the lid 6, as clearly indicated in Figs. 1 and 4 of the 75 drawings.

The closed top 4 of the shell 3 is provided with the tubular bushings 11 and 12, secured thereto in any convenient manner, preferably by forcing the same in suitable apertures formed in the closed end 4 of the shell 3, the bushing 12 being designed to receive one end of the wick 13, and the other bushing 11 designed to receive the outwardly projecting end of the steel striker 10 carried 85 by the lid 6, the bushing 11 also serving as a means through which gasoline, benzine, or the like, may be introduced to the absorbent material 14 surrounding the wick 13, and approximately filling the interior of the 90 shell 3.

15 represents a sheet metal channeled receptacle designed to receive a spark-producing element 16, the under side of said channeled receptacle being provided with integral nibs 17, designed to be passed through suitable apertures in the closed end of the shell 3 and clenched over on the under side thereof, to firmly secure said channeled-receptacle 15 with its spark producing element 100 16 to the top of the shell 3.

In Fig. 2 of the drawings, I have illustrated the channeled receptacle with its spark-producing element 16 secured to the outside of the cover 6, in the manner above 105 described, and have shown one end of the steel striker 18 secured to a post 19, provided with a grooved extension 20, said grooved extension being passed through a suitable aperture in the closed end 4 of the shell 3, 110 and the metal of said closed end being forced into intimate engagement with the

grooved extension 20 of the striker receiving post 19, to firmly secure the post 19 with its attached striker 18 to the shell 3 in a simple and inexpensive manner without the use of 5 solder.

In assembling the device, after the wick 13 has been passed through the tubular bushing 12 of the shell 3, and the shell filled with absorbent material 14, said shell 3 is placed 10 in the shell 1 so as to project a short distance above the top of the same. The steel striker 10 projecting beyond the edge of the cover 6 is intended to enter the tubular bushing 11 when the lower edge of the lid 6 engages with the shoulder 5. By removing 15 the lid, as illustrated in Fig. 1 of the drawings, and passing the striker 10 over the spark producing element 16 in the direction toward the wick 13, the sparks emitted 20 from said alloy will ignite the wick. In order to saturate the absorbent material with gasoline, benzine, or the like, it will only be necessary to withdraw the shell 3 from the shell 1 and the gasoline, benzine, or 25 the like may be introduced into the open end of the shell 3. However, should it not be desired to separate the shells, the gasoline may be introduced through the tubular bushing 11. 30 Experience has demonstrated that the above organization is a highly efficient one, and while the arrangement of the various parts as illustrated, is the preferred form of my invention, I do not care to be limited 35 to the exact details of construction as shown and described, as obvious modifications

thereof will appear to those skilled in the art.

I claim:

1. An igniter comprising a pair of shells 40 fitted into each other so as to form a closed receptacle, a spark producing alloy secured to the top of said receptacle, an absorbent material located within said receptacle, a wick projecting therefrom, a striker receiving element secured to and projecting within said receptacle, a lid for said receptacle, a striker secured to the inside of said lid and projecting beyond the edge thereof and adapted to be received by said striker receiving element when the receptacle is closed. 45
2. An igniter comprising a pair of shells fitted into each other so as to form a closed receptacle, a spark producing alloy secured to the top of said receptacle, means for securing said alloy to said receptacle, said means comprising an open-ended channeled element provided with integral tongues designed to have holding engagement with the receptacle, an absorbent material located 50 within said receptacle, a wick projecting therefrom, a lid adapted to engage with said receptacle, a spring frictionally secured in said lid, a bracket secured to one end of said spring and a removable striker carried 55 by said bracket. 60

This specification signed and witnessed this first day of December, 1913.

LOUIS V. ARONSON.
